BORING MACHINE

Lora E. Poole, Anderson, Ind., assignor, by mesne assignments, to General Motors Corporation, Detroit, Mich., a corporation of Delaware

Application March 20, 1930, Serial No. 437,478

15 Claims.

(Cl. 77—4)

This invention relates to the subject of automatic drilling or boring machines and particularly to machines for boring or machining a cylindrical surface on the interior of a tubular member.

It is an object of the present invention to provide a machine of rugged and durable construction for machining the interior of tubular bodies.

A further object of the invention is to provide for automatically controlling the operation of the boring machine in a manner such that all of the operations are performed automatically when once the machine has been set into operation by the manipulation of a single control member and such that the machine will stop automatically and return to normal position when the piece has been machined and the work holder or chuck holding the work piece will automatically release the work and permit it to fall from the chuck by gravity.

Further objects and advantages of the present invention will be apparent from the following description, reference being had to the accompanying drawings, wherein a preferred embodiment of one form of the present invention is clearly shown.

In the drawings:

Fig. 1 is a perspective view showing portions of the right side and front elevations of the machine embodying the present invention.

Fig. 2 is a perspective view showing portions of the left hand side and front of the machine.

Fig. 3 is a fragmentary side elevation partly in vertical longitudinal section.

Fig. 4 is a sectional view on the line 4—4 of Fig. 3.

Fig. 5 is a plan view of the work holder or chuck taken on the line 5—5 of Fig. 3. Fig. 5 is partly in section taken on the line 5a—5a of Fig. 6.

Fig. 6 is a sectional view on the line 6—6 of Fig. 5.

Fig. 7 is a sectional view on the line 7—7 of Fig. 3.

Fig. 8 is a front elevation of the control apparatus for the machine.

Fig. 9 is a side view thereof looking in the direction of the arrow 9 of Fig. 8.

Fig. 10 is a plan view of the apparatus partly in section taken on the line 10—10 of Fig. 8.

Fig. 11 is a sectional view on the line 11—11 of Fig. 8.

Fig. 12 is a longitudinal sectional view taken on the line 12—12 of Fig. 8, and 12a—12a of Fig. 5, and shows the control apparatus in posi-

tion for returning the boring machine to normal position and for releasing the work from the chuck.

Fig. 13 is a view similar to Fig. 12 showing the control apparatus in position for causing the chuck to grip the work and the boring apparatus to operate upon the work.

The boring machine comprises a base 20, which supports a frame 21, having spaced brackets 22 which cooperate to support an integral cylinder 23 and bearing members 24, to which a detachable bearing member 25 is secured by screws 26. The members 24 and 25 cooperate to laterally support and guide a spindle frame 30, of rectangular external contour supporting at its upper end a gear box 31 upon the upper side of which a motor 32 is attached. Motor 32 drives a shaft 33 carrying a gear 34 which meshes with a gear 35 attached to a shaft 36 journalled in a bearing 37 provided by the gear box 31 and in a bearing 38 provided by the gear box cover 39, which provides the supporting base for the motor 32. The shaft 36 drives a gear 40 meshing with a gear 41 attached to the upper end of a boring shaft or spindle 42 journalled in tapered roller bearings 43 and 44, secured to the spindle frame 30 in proper manner as clearly shown in Fig. 3.

The spindle frame 30 provides a rack 50 meshing with a gear 51 attached to a shaft 52 journalled in bearings 53 provided by the brackets 22. The gear 51 meshes with a rack 54 attached to a vertically movable counterweight 55 which is guided during its vertical movement by rollers 56 journalled on the heads of screws 57 attached to the brackets 22. Each bracket carries two pairs of rollers 56 and the rollers of each pair are spaced apart so as to receive between them a rib 58 provided by the counter-weight 55. The mass of the counter-weight 55 is sufficient to overbalance the mass of the frame 30 and parts carried thereby so that the spindle frame 30 tends to return to upward position.

The spindle frame 30 is caused to descend by admitting a suitable fluid under pressure such as oil into the cylinder 23 between its cover 60 and a piston 61 attached to a piston rod 62 connected with the gear box 31, as shown in Fig. 3.

The spindle 42 carries at its lower end a boring bit head 65 carrying bit 66 for machining the interior of a work piece A clamped in a duct 70, to be described, attached by screws 67 to a bracket 68 which provides a splash pan 69 for receiving liquid used to lubricate and cool the work and boring bits.

The chuck 70 which is shown in detail in Figs. 55

5 and 6, comprises a frame 71, having a cylindrical bore 72 which receives chuck jaw frames 73 and 74, having cylindrical peripheries in which gear segments 75 and 76 respectively are cut. 5 Segments 75 and 76 mesh with racks 77 and 78 respectively, attached by rods 79 and 80 respectively, to pistons 81 and 82 respectively, slidably in cylinders 83 and 84 respectively, provided by cylinder block 85, clamped between end plates 86 10 and 87, with screws 88 secured to the frame 71. The chuck jaw frame 73 is confined between the jaw frame 74 and the bracket 68. The chuck jaw frame 74 is confined between the jaw frame 73 and the bottom plate 89, secured by screws 90, 15 to the frame 71. Each of the jaw frames 73, 74 is provided with radial notches 91 each of which guides for radial movement a chuck jaw 92, having teeth 93 for gripping the work piece A and having a projection 94 cooperating with a stationary camming surface 95, provided by the frame 71. The projections 94 are normally urged 20 against the cams 95 by leaf spring members 96, each attached by screws 97 to one of the chuck jaw frames and each extending from a screw 97 25 through a knot 98 provided in the chuck jaw frame and into a recess 99 provided in the chuck jaw. When the pistons 81 and 82 move toward the right as viewed in Figs. 5 and 13, the frames 73 and 74 will rotate in the direction of the arrow 100, thereby causing the chuck jaw projections 94 to ride along those portions of the cams 95 which are nearer to the center of the chuck, thereby causing the work piece A to be firmly gripped by the jaws 92. When the pistons 81 and 82 move 30 toward the left as in Fig. 12, the motion of the chuck frames 73 and 74 will take place in the direction of the arrow 101, thereby causing the chuck jaw projections 94 to ride progressively toward portions of the cams 95 which are more remote from the center of the chuck, whereupon the jaws will recede from the work piece A to permit the same to descend by gravity into the container 102, shown in Figs. 1 and 2.

The control of the admission of pressure fluid 45 to the cylinders 23, 83, and 84 will now be described with reference to Figs. 8 to 13 inclusive. To the front face 110 of the spindle frame cover and guide member 25, there is secured a plate 111 shown in Figs. 1 and 2, 8 to 13, inclusive, but 50 omitted from Figs. 3 and 4. The plate 111 supports a valve body 112 to which end members 113 and 114 are secured, said end members providing brackets by which the body 112 is attached to the plate 111. The plate 111 supports a 55 valve body 30 having end members 131 and 132 which are used to attach the body 130 to the plate 111. The body 112 is provided with a central bore 115 and the body 140 with a central bore 133 in alignment with the bore 115. The body 112 receives a valve rod 116 providing cylindrical valves 117 and 118 for controlling ports 119, 120, and 121 connected respectively with pipes 122, 123 and 124. A spring 125 tends to maintain the valve rod 116 in upper position shown 60 in Fig. 12. The pipe 123 is connected with the cylinder 23 between the piston 61 and the cylinder head 60. The pipe 122 returns the pressure fluid to the low pressure side of a compression pump. Pipe 124 is connected with the high pressure side of a compression pump or reservoir of fluid under pressure.

The spring 125, which lifts the valve 116, surrounds a rod 126 attached to the valve 118 and adapted to transmit downward movement from 75 valve 118 to a valve rod 134 which slides through

the valve body 130 and has valves 135 and 136 for controlling ports 137, 138, 139, and 140 connected respectively with pipes 141, 142, 143, and 144. Pipe 141 is connected with branch pipes 141a and 141b communicating with the right ends of the cylinders 83 and 84 respectively. Pipe 142 is connected with a sort of fluid under pressure. Pipe 143 is connected with branch pipes 143a and 143b communicating with the left hand ends of the cylinders 83 and 84 respectively. Pipe 144 leads back to a liquid reservoir open to the atmosphere or to the low pressure side of a compression pump. The valve rod 134 is normally maintained in elevated position shown in Fig. 12, by a spring 145 surrounding a rod 146 attached to the valve rod 134. The valve rod 134 is provided with a central passage 147 communicating with side passages 148 and 149. When the valve 134 moves upwardly, these passages provide for the transfer of liquid from that portion of the valve housing 130 which is above the valve 135 to that portion of the valve housing 130 which is below the valve 136, and vice versa, when the valve 134 moves downwardly.

Normally, the valve rods 116 and 134 are in upper position as shown in Figs. 8, 9, and 12. When the valves are in this position, the upper end of the cylinder 23 is connected with the liquid drain pipe 122 as indicated by arrows 150, 151, 152, and 153. Likewise, the right hand ends of the cylinders 83 and 84 are connected with the high pressure supply pipe 142, as indicated by arrows 154, 155 and 156, to cause the pistons 81 and 82 to move toward the left, as indicated by arrows 157, thereby causing the chuck jaws to be located in non-clamping position. To use the machine, the operator will pass a work piece A upwardly through the central opening in the chuck 70 until the work piece strikes a stop plate 68a, attached to the bracket 68, as shown in Fig. 3. While maintaining the piece A in this position with one hand, the operator pulls down on a handle 160, thereby causing a lever 161, pivoted at 162 upon the plate 111, to move into the position indicated in dot and dash line 161a. The lever, being connected by a pin 163 to a bifurcated block 164 attached to the valve rod 116, will cause the valve rods 116 and 134 to move from the positions shown in Fig. 12 to those shown in Fig. 13. These valve rods will be held in these positions by a latch 165, attached to a lever 166, pivoted at 167 upon the plate 111, and urged by spring pressed plunger 168 in a clockwise direction so that the latch 165 will engage the under side of the lever 161 to hold it in the dot-dash line position 161a. Movement of the valve rod 116 into the position shown in Fig. 13 will cause the upper end of the cylinder 23 to be connected with the high pressure pipe 124 as indicated by arrows 170, 171, 172, and 173 in order to cause the piston 61 to move downwardly, as indicated by arrows 174. The movement of the valve rod 134 into the position shown in Fig. 13 will cause the high pressure pipe 142 to be connected with the left hand end of the cylinders 83 and 84 as indicated by arrows 175, 176, and 177, in order to cause the pistons 81 and 82 to move toward the right as indicated by arrows 178. Consequently, the work piece A will be clamped in the chuck while the spindle frame 30 descends due to the force exerted upon the upper side of the piston 61, as indicated by arrows 174. As the frame descends, the rotating spindle 42 will cause the tools 66 to machine a cylindrical surface upon the interior of the work piece A.

After the tools 66 have descended below the work piece A, the spindle frame 30 will be caused to ascend automatically, but the chuck 70 is not automatically released until after the tools 66 have ascended above the work piece. Referring to Figs. 8, 9, and 11, it will be noted that a latch bar 180 slidable in a bracket 181, is urged by a spring 182 toward the right against the valve rod 134. When the rod 134 is moved into the position shown in Fig. 13 by the downward movement of the rod 126, the latch 180 will move into the position indicated by dot and dash line 180a in Fig. 8, so that it will be over the upper end of the valve rod 134 when in the position shown in Fig. 13 and will bear against the rod 126 when in the position shown in Fig. 13 or in the dot-dash line position 126a shown in Fig. 8. The gear housing 31 carries a bracket 183 from which a rod 184 is suspended, said rod being guided by a bracket 185 attached to the plate 111. The rod 184 carries collars 186 and 187 which are adjustably secured to the rod 184. By the time the tools 66 have descended below the work piece A, the collar 186 will have descended slightly below the position 186a shown in Fig. 8, in order to engage the latch lever 166 and to cause it to move counterclockwise in order to move the latch 165 away from the lever 161, whereupon the spring 125 in the valve housing 112 will cause the rod 116 to move upward carrying with it the lever 161, which moves from position 161a into the normal position shown in full lines in Fig. 8. The return of the valve rod 116 to normal position will cause the pressure upon the upper side of the piston 61 to be released and the pressure fluid to flow from the cylinder 23 in the manner indicated by arrows 150, 151, 152, and 153. The counter-weight 55, being heavier than the spindle frame 30 and parts carried thereby, will cause the frame to be elevated carrying the tools 66 above the work piece A. By the time the tools 66 have arrived above the work piece A shown in Fig. 3, the collar 187 will have engaged a bell-crank lever 190, pivoted at 191 upon the bracket 181 to move clockwise, thereby causing its lever arm 192, which is received by a knot 193 in the latch bar 180, to move said latch bar toward the left so that it will be out of alignment with the upper end of the valve rod 134, whereupon the spring 145 in the housing 130, will be permitted to return the valve rod 134 into the position shown in Fig. 12. When this occurs, the pistons 81 and 82 will move from the position shown in Fig. 13 to the position shown in Fig. 12, thereby retracting the chuck jaws from the work piece and permitting the work piece to descend by gravity into a receptacle 102 shown in Figs. 1 and 2. It will be noted that the total pressure exerted upon the right hand ends of the pistons 81 and 82 is greater than that exerted upon the left hand ends on account of deduction for cross sectional area of the piston rod. This circumstance is taken advantage of because it is desirable that the pressure operating to unclamp the clamps of the work piece be greater than that required to move them into clamping position. When the clamps are moved into clamping position, the frictional resistance encountered between the projections 94 of the chuck jaws 92 and the cams 95, is a sliding friction, the coefficient of which is less than the coefficient of static friction to be overcome first, before the chuck jaw frames 73 and 74 can be started rotating in a counter-clockwise direction, as viewed in Fig. 5 to effect release of the chuck jaws.

75 If for any reason it is desired to stop downward

movement of the boring spindle while in operation, the operator may pull a handle 200 downwardly to cause the lever 166 to move into a position for releasing the lever 161, whereupon the spindle frame 30 will ascend and the work piece will be automatically released from the chuck.

While the form of embodiment of the present invention as herein disclosed, constitutes a preferred form, it is to be understood that other forms might be adopted, all coming within the scope of the claims which follow.

What is claimed is as follows:

1. A boring machine comprising, in combination, a workholding chuck; a tool carrying spindle movable toward and away from the chuck; fluid pressure operated means for advancing the spindle toward the work; gravity means for retracting the spindle; a supply of fluid pressure; a first control means normally urged into a position in which to intercept communication between the fluid supply and the spindle advancing means; manually operable means for shifting the control means into communicating position; means for arresting the control means in communicating position; power means for causing the chuck to grip the work; a second control means operated by the movement of the first control means into communicating position for rendering the power means effective; means adjustably carried by the spindle for disengaging the arresting means from the first control means upon engagement with the same; and means for operating the second control means so as to render the power means ineffective.

2. A boring machine comprising, in combination, a workholding chuck; a tool carrying spindle movable toward and away from the chuck; fluid pressure operated means for advancing the spindle toward the work; gravity means for retracting the spindle; a supply of fluid pressure; a first control means normally yieldingly urged into a position in which to intercept communication between the fluid supply and the spindle advancing means; manually operable means for shifting the control means into communicating position; means for arresting the control means in communicating position; power means for causing the chuck to grip the work; a second control means operated by the movement of the first control means into communicating position for rendering the power means effective, and operated by the retracting spindle for rendering the power means ineffective; and means adjustably carried by the spindle for disengaging the arresting means from the first control means upon engagement with the same.

3. A boring machine comprising, in combination, a workholding chuck; a tool carrying spindle movable toward and away from the chuck; fluid pressure operated means for advancing the spindle toward the work; gravity means for retracting the spindle; a supply of fluid pressure; a first control means normally yieldingly urged into a position in which to intercept communication between the fluid supply and the spindle advancing means; manually operable means for shifting the control means into communicating position; means for arresting the control means in communicating position; fluid pressure operated means for causing the chuck to grip the work; a second control means yieldingly urged into a position in which to intercept communication between the fluid supply and the last said fluid pressure operated means, and shifted into

communicating position by the first control means when moving into communicating position; means arresting the second control means in communicating position; means adjustably carried by the spindle for disengaging the arresting means from the first control means upon engagement with the same; and means for disengaging the arresting means from the second control means.

10 4. A boring machine comprising, in combination, a workholding chuck; a tool carrying spindle movable toward and away from the chuck; fluid pressure operated means for advancing the spindle toward the work; gravity means for re-
15 tracting the spindle; a supply of fluid pressure; a first control means normally yieldingly urged into a position in which to intercept communication between the fluid supply and the spindle advancing means; manually operable means for
20 shifting the control means into communicating position; means for arresting the control means in communicating position; fluid pressure operated means for causing the chuck to grip the work; a second control means yieldingly urged
25 into a position in which to intercept communication between the fluid supply and the last said fluid pressure operated means, and shifted into communicating position by the first control means when moving into communicating position;
30 means for arresting the second control means in communicating position; means adjustably carried by the spindle for disengaging the arresting means from the first control means upon engagement with the same; and means adjustably carried by the spindle for disengaging the arresting means from the second control means upon engagement with the same.

5. A boring machine comprising, in combination a machine frame, a work holding chuck, a
40 tool-carrying spindle movable axially toward or away from the chuck, means for axially moving the spindle, means for operating the chuck, a controller operable to cause the chuck to grip and release the work, another controller operable to
45 cause the spindle to move toward the work; manually operated means to actuate both controllers simultaneously in order simultaneously to close the chuck and to start the spindle toward the work; and automatic means for stopping the movement of the spindle toward the work and for causing the spindle to recede and for causing the chuck to release the work after the tool on the spindle completely retracted from the work, said automatic means including a plurality
55 of relatively movable coacting parts carried respectively by the machine frame and the spindle, the parts carried by the spindle being adjustable thereon and devices operating upon each controller in response to the coaction of said parts.

60 6. A boring machine comprising, in combination, a machine frame; a work holding chuck, a tool-carrying spindle movable axially toward or away from the chuck, means for axially moving the spindle, fluid pressure means for operating
65 the chuck, a controller operable to cause the fluid pressure means to open and close the chuck; another controller operable to cause the spindle to move toward the chuck; manually operated means to operate both controllers simultaneously in order simultaneously to effect closing of the
70 chuck and to start the spindle toward the work; and automatic means for stopping the movement of the spindle toward the work and causing the spindle to recede, and for causing the fluid pressure operated means to open the chuck to release

the work after the tool on the spindle completely retracted from the work, said automatic means including relatively movable coacting parts carried respectively by the machine frame and the spindle, the parts carried by the spindle being adjustable thereon and devices operating upon each controller in response to the coaction of said parts.

7. A boring machine comprising, in combination, a machine frame; a work holding chuck, a tool-carrying spindle movable axially toward or away from the chuck, fluid pressure operated means for causing the spindle to move toward the chuck, fluid pressure means for operating the chuck; yielding means for retracting the spindle; a controller operable to cause the fluid pressure means to open and close the chuck; another controller operable to cause the fluid pressure operated means to move the spindle toward the work; manually operated means to actuate both controllers simultaneously in order simultaneously to cause the fluid pressure means to close the chuck and to cause the fluid pressure operated means to start the spindle toward the work; and automatic means for causing the fluid pressure operated means to stop movement of the spindle toward the work and to render the fluid pressure operated means ineffective and for causing the fluid pressure means to open the chuck to release the work after the tool on the spindle completely retracted from the work, said automatic means including a plurality of relatively movable coacting parts carried respectively by the machine frame and the spindle, the parts carried by the spindle being adjustable thereon and devices operating upon each controller in response to the coaction of said parts.

8. A boring machine comprising, in combination, a machine frame; a work holding chuck, a tool-carrying spindle movable axially toward or away from the chuck, means for axially moving the spindle, means for operating the chuck, a controller operable to cause the chuck to grip and release the work; another controller operable to cause the spindle to move toward the work; manually operated means to actuate both controllers simultaneously in order simultaneously to close the chuck and to start the spindle toward the work; automatic means for stopping the movement of the spindle toward the work and for causing the spindle to recede and the chuck to release the work after the tool on the spindle completely retracted from the work, said automatic means including a plurality of relatively movable coacting parts carried respectively by the machine frame and the spindle, the parts carried by the spindle being adjustable thereon and devices operating upon each controller in response to the coaction of said parts; and manually operable means for operating certain of said parts on the machine frame at will thereby effecting interruption of the movement of the spindle toward the work at will.

9. A boring machine comprising, in combination, a workholding chuck; a tool-carrying spindle; means for causing relative movement between the spindle and the chuck; means for operating the chuck; a first controller operable to cause the chuck to grip and release the work; a second controller operable to cause relative movement between the spindle and the chuck; manually operated means to actuate both controllers simultaneously in order simultaneously to effect closing of the chuck and relative movement between the spindle and the chuck in one direction;

- means for actuating said second controller for causing to stop the relative movement between the spindle and chuck in said one direction and for causing relative movement between the spindle and chuck in the other direction; and means for actuating the first controller for causing the chuck to release the work.
10. In material working apparatus, a multi-sided sleeve having oppositely disposed bearing surfaces, a rotatable spindle within said sleeve, means for rotating said spindle, a mounting having oppositely disposed bearing surfaces for receiving and guiding the bearing surfaces of said sleeve to thereby secure said sleeve against lateral displacement and torsion, said sleeve being adapted for reciprocation within said mounting to effect the translation of said spindle, a reciprocable hydraulic actuator including a piston and cylinder construction for imparting translation 15 to said sleeve, said sleeve extending in the direction of travel of said actuator and cooperating to maintain the alinement of said actuator during the operative functioning thereof, and means carried by said sleeve as a unit thereof 20 and rigidly connecting said sleeve with said actuator.
11. In material working apparatus, a multi-sided reciprocable sleeve for internally supporting a spindle, a rotatable spindle in said sleeve, means for rotating said spindle, a hydraulic actuator including a piston and cylinder construction for imparting reciprocation to said sleeve, and a unitary mounting for maintaining the alinement of said hydraulic actuator and said 25 sleeve during the longitudinal translation thereof, said mounting forming a portion at least of the cylinder structure of the actuator whereby to present a compact, rigid unitary construction.
- 40 12. In material working apparatus, a multi-sided sleeve having oppositely disposed bearing surfaces, a rotatable spindle within said sleeve, means for rotating said spindle, a mounting having oppositely disposed bearing surfaces for receiving and guiding the bearing surfaces of said sleeve to thereby secure said sleeve against lateral displacement and torsion, said sleeve being adapted for reciprocation within said mounting to effect the translation of said spindle, a reciprocable hydraulic actuator including a piston and cylinder construction positioned laterally of said sleeve for imparting reciprocation thereto, the multi-sided sleeve extending in the direction of travel of said actuator and cooperating 45 to maintain the alinement of said actuator during the operative functioning thereof and means
- carried by said sleeve as a unit thereof and rigidly connecting said sleeve with said actuator.
13. In material working apparatus, a multi-sided sleeve having oppositely disposed bearing surfaces, a rotatable spindle within said sleeve, means for rotating said spindle, a mounting having oppositely disposed bearing surfaces for receiving and guiding the oppositely disposed bearing surfaces of said sleeve to thereby secure said sleeve against lateral displacement and torsion, 5 said sleeve being adapted for reciprocation within said mounting to effect the translation of said spindle, means for securing said sleeve within said mounting, a hydraulic actuator positioned adjacent and laterally of said sleeve, said sleeve extending in the direction of travel of said actuator and cooperating to maintain the alinement of said actuator during the operative functioning thereof and means carried by said sleeve as a unit thereof and rigidly connecting said 10 sleeve with said actuator.
14. In material working apparatus, a multi-sided sleeve having oppositely disposed bearing surfaces, a rotatable spindle within said sleeve, means for rotating said spindle, a mounting having oppositely disposed bearing surfaces for receiving and guiding the bearing surfaces of said sleeve to thereby secure said sleeve against lateral displacement and torsion, said sleeve being adapted for reciprocation within said mounting to effect the translation of said spindle, a hydraulic actuator including a cylinder and a piston reciprocable therein for imparting translation to said spindle, said actuator being positioned laterally of and in substantial parallelism 15 with the axis of said spindle, the sleeve cooperating to maintain the alinement of said actuator during its operative functioning and means carried by said sleeve as a unit thereof and connecting said sleeve with said actuator.
- 20 15. In material working apparatus, a unitary frame having oppositely disposed bearing surfaces, a hydraulic actuator including a piston and a piston rod reciprocably mounted within said frame, a multi-sided sleeve reciprocably mounted within said unitary frame and having bearing surfaces adapted to be received and guided by the bearing surfaces of said frame, said sleeve being spaced from and arranged in substantial parallelism with the axis of said actuator piston, a spindle rotatably mounted within said sleeve, 25 a rigid connection between said sleeve and said actuator, and means for imparting rotation to said spindle.

LORA E. POOLE. 55
